UNITED STATES PATENT OFFICE.

WILLIAM P. FEENEY, OF HUDSON FALLS, NEW YORK, ASSIGNOR OF ONE-FOURTH TO
WILLIAM GERMAIN, OF FORT EDWARD, NEW YORK.

AUTOMATIC STUFF-BOX FOR PAPER-MACHINES.

1,134,831

Specification of Letters Patent.

Patented Apr. 6, 1915.

Application filed December 31, 1913. Serial No. 809,769.

To all whom it may concern:

Be it known that I, WILLIAM P. FEENEY, a citizen of the United States, and a resident of Hudson Falls, in the county of Washington and State of New York, have invented a new and Improved Automatic Stuff-Box for Paper-Machines, of which the following is a full, clear, and exact description.

My invention has for its object to provide 10 a stuff box for use in paper machines having means actuated by a float for regulating the flow of the stock to a paper machine and for returning the surplus stock to the chest.

Additional means are provided for adjusting 15 the first mentioned means for the manufacture of paper of different weights and for regulating the flow of the stock with reference to the speed at which the paper machine is driven.

Still another object of the invention is to 20 provide means to return the stock to the chest before it reaches the float.

Additional objects of the invention will 25 appear in the following specification in which the preferred form of my invention is described.

In the drawings similar reference characters refer to similar parts in all the views in which—

30 Figure 1 is a view showing how my stuff box may be used in a paper making machine; Fig. 2 is a sectional view on the line 2—2 of Fig. 1; Fig. 3 is a plan view of the stuff box; Fig. 4 is an enlarged sectional view on the 35 line 4—4 of Fig. 3; and Fig. 5 is an enlarged sectional view on the line 5—5 of Fig. 3.

By referring to the drawings it will be seen that the stock is forced up in the pipe 10 into a compartment 11 in the casing 12, 40 this compartment 11 being separated from the compartment 13 by a partition 14, the compartment 11 also being separated from the return passage 15 by the partition 16. The partition 14 is disposed longitudinally 45 of the casing 12 and the partition 16 is disposed transversely of the casing 12 from the partition 14 to an outer wall of the casing. In the partition 16 there is an opening 17 which is normally closed by a valve 18, this 50 valve 18 being disposed for moving in guide-ways 19 and having a slotted arm 20 in which is disposed a crank 21 on a shaft 22, this shaft 22 being journaled in bearings 23 and 24 in a wall of the casing 12 and in the 55 partition 14. It will be understood that the

shaft 22 may be rotated by the hand-wheel 24 at the outer side of the casing 12, which, with the crank 21 and the slotted arm 20, serves as a means to raise or lower the valve 18 as may be desired. When the valve 18 is 60 raised, the stock, which flows up in the pipe 10 to the compartment 11, will pass through this opening 17 to the return passage 15 and back through the pipe 25 to the stock chest which is not shown in the drawings. 65

When the stock is to be used in the paper machine, the valve 18 is lowered to close the opening 17. The stock will then accumulate in the compartment 11 and flow over the top of the partition 14 which is lower than the 70 top of the partition 16. The stock will then accumulate in the compartment 13. This compartment 13 is provided with two outlets 26 and 27, the outlet 26 being located in the partition 14 and affording communication 75 between the compartment 13 and the return passage 15. The outlet 27 is located in an outer wall of the casing 12 and serves to direct the stock to the mixing box 28 where the stock is mixed with water, the stock 80 mixed with water passing to the pump 29 from which it is forced through the pipe 30 to the screen 31 and through the screen compartment 31 to the head box 32, from which the stock is fed to the wire screen in the cus- 85 tomary manner. In the partition 14 at the sides of the outlet 26 there are guideways 33 in which a valve member 34 is disposed, this valve member 34 having an orifice 35, in which is disposed a bolt 36, the bolt 36 also 90 passing through a slot in a flange 37 on a yoke 38, a collar 36^a being disposed on the said bolt 36 and being held against the flange 37, at the sides of the slot therein by the nut 36^b. By this means it is possible to 95 adjust the position of the valve member 34 relatively to the yoke 38. At the sides of the outlet 27 there are guideways 39 in which a valve member 40 is adapted to move. The valve member 40 has an opening 41 adapted 100 to register with the outlet 27, the upper portion of the valve member 40 being secured to the flange 42 of the yoke 38. To this yoke 38 there is secured a rod 43 which passes through an opening 44 in a platform 45, the platform 45 being supported by the rods 46 above the top of the casing 12. The upper portion of the rod 43 is threaded at 47 and this threaded portion of the rod 43 is dis- 105 posed through an opening in a bracket 48, 110

the bracket 48 being secured to the top of the platform 45. Meshing with the thread 47 on the rod 43 above and below the bracket 48 there are wheels 49, it being possible to 5 turn these wheels 49 home against the bracket 48 to hold the rod 43 and the yoke 38 in adjusted position. As has been stated, it is possible to adjust the valve member 34 relatively to the yoke 38 and the valve member 40. When the adjustment has been made 10 and the screw has been turned home, it will be seen that by raising the rod 43 and the yoke 38, that the valve member 34 will be moved upwardly relatively to the outlet 26 to expose a greater area between the bottom 15 of the valve member 34 and the bottom of the outlet 26. When the yoke 38 has been raised to move the valve member 34 upwardly in the manner described, it will raise 20 the valve member 40 so that the portion of the valve member 40 below the opening 41 in the valve member will be raised to cover a greater portion of the area of the outlet 27. When the outlet passage to the mixing box 25 is increased in area, the outlet 26 to the return passage 15 is decreased in area, while when the outlet to the return passage 15 is increased in area the passage to the mixing box is decreased in area. The exposed areas 30 of the outlets 26 and 27 are adjusted for the manufacture of different weights of paper and as may be necessary when there is a change of speed in the operation of the paper making machine.

35 In the operation of the machine, the stock will flow, as has been stated, into the compartment 11, and under normal conditions, it will not serve to raise the float, but when the stock becomes thick or the throw of the 40 pump increases, it raises the float. To this float there is secured a sleeve 51 in which is disposed a rod 52, the rod 52 being held in the sleeve 51 by the set screw 53. The rod 52 passes through an opening 54 in the table 45 and to this rod 52 there are secured 45 two levers 55 and 56. The lever 55 is fulcrumed on a bracket 57 mounted on the table 45, and the lever 56 fulcrumed on a bracket 58 mounted on the table 45. To the 50 arm 59 of the lever 55 there are secured rods 60, these rods 60 passing through an opening in the table 45 and being secured to the arms 61 which are fulcrumed at 62 to the brackets 63, the brackets 63 being 55 secured to the partition 14 at the sides of the outlet 26. To the arms 61 there is secured a valve 64 for closing or partially closing the outlet 26. To the arm 65 of the lever 56 there are secured rods 66, these 60 rods 66 being articulated to arms 67, pivoted at 68 to the brackets 69, the brackets 69 being secured at each side of the outlet 27 to the outer side of the casing 12. To the arms 67 there is secured a valve 70. In 65 the operation of the valve 70 the valve

moves above the outlet 27 to expose the outlet, while in the operation of the valve 64, the valve 64 moves below the outlet 26 to expose the outlet. It will, therefore, be seen that when the stock becomes thick or 70 the throw of the pump increases beyond normal, it will raise the float 50 and by means of the levers described, will press on the rods 60 and 66 to expose a greater area 75 of the outlet 26 and to close or partially close the outlet 27. In this way the even flow of the stock may be maintained under all conditions.

Having thus described my invention I claim as new and desire to secure by Letters Patent:

1. In an automatic stuff box for paper machines, a casing having an inlet and two outlets, guideways in the casing adjacent the outlets, two valve members disposed in 85 the guideways, one adjacent the top of one of the outlets and the other adjacent the bottom of the other outlet, a yoke to which the valve members are rigidly secured for raising one of the valve members to expose 90 a greater area in one outlet as the other valve member is raised for closing a greater area in the other outlet, two valves, one disposed at the exposed area of each outlet, a float in the casing, and means operable 95 by the float for simultaneously moving one of the valves for closing a portion of the exposed area of one of the outlets as the other valve uncovers a portion of the exposed area of the other outlet. 100

2. In an automatic stuff box for paper machines, a casing having an inlet and two outlets, guideways in the casing at the sides of the outlets, a valve member for moving in one of the guideways at one outlet, a yoke, means for adjusting the valve member on the yoke, a valve member secured to the yoke for moving in the other guideway, means for holding the yoke in adjusted position, two valves, one of each outlet, a float in the casing, and means connecting the float with the valve for simultaneously moving one of the valves for closing a portion of the exposed area of one of the outlets, as the other valve uncovers 110 a portion of the exposed area of the other outlet. 115

3. An automatic stuff box for paper machines, a casing having two partitions dividing the casing into three compartments, there being an inlet into the first compartment and an outlet from an adjacent second compartment, the top of the partition between the said first and second compartments being lower than the top of the partition between the first and third compartment, an outlet from the second compartment to the third compartment, a float in the first compartment, two valves, one disposed at each outlet, means operable by the 120 125 130

float for simultaneously moving one of the valves for partially closing one of the outlets, while the other valve is moved to uncover a greater area of the other outlet, there
5 being in one of the partitions an opening between the first and third compartments, and a valve for closing the said opening.

In testimony whereof I have signed my name to this specification in the presence of the two subscribing witnesses.
